The ornamental design for a head mounted display with headtracker, as shown.

DESCRIPTION

FIG. 1 is a perspective view of the head mounted display with headtracker;

FIG. 2 is a front elevational view of the head mounted display with headtracker;

FIG. 3 is a rear elevational view of the head mounted display with headtracker;

FIG. 4 is a right side elevational view of the head mounted display with headtracker;

FIG. 5 is a left side elevation view of the head mounted display with headtracker;

FIG. 6 is a top plan view of the head mounted display with headtracker; and,

FIG. 7 is a bottom plan view of the head mounted display with headtracker.
